SWIMMING POOL TOY

Roger A. Del Mar and Bern Wolf, Los Angeles County,
Calif., assignors to Aeroplastics Corporation, Venice,
Calif., a corporation of California

Filed Dec. 11, 1961, Ser. No. 67,856

Term of patent 14 years

(Cl. D34—15)

We claim:

The ornamental design for a swimming pool toy, as shown.
